US0D1073487S

(12) **United States Design Patent** (10) **Patent No.:** **US D1,073,487 S**
(45) **Date of Patent:** **** May 6, 2025**

(54) **CONNECTOR FOR WATCHES**

(71) Applicant: **BEIJING XIAOMI MOBILE SOFTWARE CO., LTD.**, Beijing (CN)

(72) Inventor: **Huacan Cui**, Beijing (CN)

(**) Term: **15 Years**

(21) Appl. No.: **35/518,664**

(22) Filed: **Sep. 26, 2023**

(80) **Hague Agreement Data**

Int. Filing Date: **Sep. 26, 2023**

Int. Reg. No.: **DM/232019**

Int. Reg. Date: **Sep. 26, 2023**

Int. Reg. Pub. Date: **Oct. 13, 2023**
